GEORGE WEBB, OF WEST HARTFORD, AND FRANK D. JENKS, OF HARTFORD, CONNECTICUT, ASSIGNORS TO COLT'S PATENT FIRE ARMS MANUFACTURING COMPANY, OF HARTFORD, CONNECTICUT, A CORPORATION OF CONNECTICUT

DOOR-OPERATING MECHANISM

Application filed October 16, 1925. Serial No. 62,857.

A door operating mechanism embodying the invention is particularly adapted for use in a dish washing machine of that class in which the washing and rinsing liquids are sprayed or otherwise thrown against the articles being washed while the same are located inside of an enclosed casing or cabinet.

In this class of dish washing machines, a vertically slidable door or doors are commonly provided to permit the insertion and removal of the articles being washed, but which are closed during the washing and rinsing operation to confine the washing and rinsing fluids within the casing.

Heretofore, to provide for ease of operation the door or doors have been partially counterbalanced by weights connected to the doors by means of chains passing over a pulley or pulleys, but the use of such weights is objectionable for several reasons. If the doors are rapidly opened, the momentum of the weights is very liable to break the chains. If the weight is arranged inside the casing, it is then difficult to recover it from the bottom of the casing, and if arranged on the outside of the casing the weight is liable to injure the operator or otherwise cause damage when torn from its chain. If the weight is arranged at the back of the machine near a wall, its path is liable to be stopped by any obstruction thrown back of the machine by a careless operator, which obstruction will interfere with the operation of the doors until removed.

One object of the invention is to overcome these and other disadvantages by providing a novel improved door operating means for machines of this class, which dispenses with the use of weights, while, at the same time, retaining the advantages of such weights in providing ease of operation.

A more specific object of the invention is to provide a manually operable mechanism for opening and closing the doors located in an improved and more convenient relationship to the other parts of the dish washing machine.

Another specific object of the invention is to provide a door opening and closing mechanism for a dish washing machine having an

operating lever arranged in a novel and improved way.

Still another specific object of the invention is to provide a door operating mechanism having an improved spring means connected with the door or doors. 55

Still further objects of the invention will be apparent from the following specification and claims.

In the accompanying drawings we have 60 illustrated the invention as applied to a dish washing machine of the class already referred to. It will be understood that the details of the door operating mechanism itself may be varied and that the particular embodiment of the invention shown has been selected merely for purposes of illustration and that the drawings are not to be construed as defining or limiting the invention, the claims forming a part of this specification being relied upon for that purpose. 65 70

Of the drawings—

Fig. 1 is a perspective view of a washing machine embodying the invention;

Fig. 2 is a plan view of the machine with 75 the door operating mechanism in closed position;

Fig. 3 is a front elevation of the machine, with parts broken to expose the door operating mechanism in its closed position. In 80 this view the ends of the chains, secured to the lever, are not shown, and the right hand chain is not shown traversing the double pulley;

Fig. 4 is an enlarged view showing the 85 door operating lever stop;

Fig. 5 is an enlarged plan view of the chain connection on the door operating handle;

Fig. 6 is an enlarged vertical view of the parts shown in Fig. 5; 90

Fig. 7 is an enlarged inside view of the chain connection to a door;

Fig. 8 is an enlarged vertical central section through the lower portion of the door adjacent casing parts; and 95

Fig. 9 is an enlarged vertical view of a portion of the operating lever and pivot and with parts of the machine thereabout broken away.

Referring to the several figures of the 100

drawing, in which corresponding parts are indicated by the same reference characters.

In the embodiment of the invention selected for illustration there is shown a dish washing machine having casing or cabinet 1 substantially rectangular in cross-section, the lower part of which contains a tank 2 for holding washing and rinsing liquids and the upper portion of which is provided with supporting rails or devices 3 for the articles to be cleaned. The usual means are provided for treating the articles with the cleaning liquids while so supported, comprising motor 4 and liquid circulating pipes 5 and 6. The pipe 5 is connected with suitable spray devices, such as 5^a, adapted to deliver the washing liquid against dishes supported by the said supporting devices 3. To permit the articles to be inserted at one side of the machine, one side wall is provided with a large opening normally closed by a door 7 which is preferably slidable. In order that the articles may be removed at the other side, the wall at the said other side is preferably provided with a similar large opening also normally closed by a similar door 7. Adjacent the openings in the casing for the insertion and removal of the articles being washed, suitable tables (not shown) may be provided to facilitate the handling of the articles when placed in or removed from the machine.

When two doors are provided as shown we provide a door opening and closing mechanism having its major portions behind the front wall of the casing but including an operating lever which extends in front of the front wall so as to be conveniently accessible for manual operation. In order to protect the said mechanism from the action of the spray devices there is preferably provided a partition within the casing which forms a separate chamber for the mechanism.

Preferably the door opening and closing mechanism is located at the top of the casing above the spray devices, and when it is so located all of the principal parts thereof are movable horizontally and the partition, when provided, is a horizontal one forming a transverse chamber at the top of the casing. As illustrated, the sides of the casing 1 are extended upwardly some distance above the top of the cleaning compartment and in one side of this upwardly extending portion adjacent the operator's position is provided a horizontal slot 8 through which projects the handle 9 of the operating lever 10 for the doors 7, 7. This operating lever is pivoted at 11 adjacent the opposite side of the casing, (see Figs. 2 and 9) and is connected to the respective doors by flexible tension elements, such as chains 12 and 13. The chains have their respective ends secured near the free end of the lever, as shown in Figs. 5 and 6, and they pass over a suitable double guiding pulley 14 and over single pulleys 15 and 16

to the lower portions of the doors. The lower ends of the chains are secured to the respective doors in any suitable manner, for example as shown in Figs. 7 and 8.

From this construction it will be seen that the operator can readily open both doors by grasping the handle of the lever and throwing it to the left, where it is conveniently held in the open position by a lug 17 provided at the bottom of the slot 8 in which the lever moves. The lever being of considerable length has sufficient play on its pivot 11 to allow it to drop behind this lug without attention on the part of the operator. The operator, when he is ready to close the machine, merely strikes the lever handle a light blow from below in grasping it, which releases it from its lug permitting the doors to close, assisted by gravity, under the control of the operator.

The before mentioned horizontal partition is shown at 17^a, and it forms a chamber at the top of the casing in which the principal parts of the door raising and lowering mechanism are located. This partition entirely protected the said mechanism from the action of the spray devices.

Preferably one or more springs are provided to partly counterbalance the door or doors. When there are two doors we preferably provide a common spring means or a single group of springs connected with both doors so as to tend to raise them. We also prefer, whether there is one door or two doors, to use coil springs located in horizontal positions and above the spray devices. When the door raising and lowering mechanism is constructed as already described the springs may be combined therewith in the manner to be now described.

One or more springs 18 are arranged to extend horizontally in the casing, being secured at one end to a fixed abutment 19 on the inside of the side wall of the casing and having its opposite end secured to a flexible tension element such as a chain 20 which passes around a guiding pulley 21 arranged adjacent the opposite wall of the housing, and which is secured to the lever at a point between its pivot and the place where the door operating chains are secured, (see Fig. 2). To provide means for readily adjusting the tension of the spring, the lever is shown provided with a plurality of spaced holes with any one of which the end of the chain may be detachably connected. It will be observed that the springs 18 have their ends at opposite sides of the lever 10, connection with the lever being made through the chain 20 as already stated. This construction enables us to provide much longer springs than would be possible if the springs were connected directly to the lever.

By the construction herein described, the tension of the spring is obviously at its maxi-

5   mum when the doors are closed, so that the effort required for starting the doors from rest in opening them is small. After the doors have been started, it will be evident that little effort will be required to continue the opening movement even though the tension of the spring is decreased as the doors approach the open position. This lessening of the tension is, in fact, desirable to avoid the slamming of the doors when they reach their full open position, which would be liable to result where a weighted counterbalance is employed.

10   A plurality of springs, two in number as shown, are preferably employed to insure that all of the counterbalancing effect is not destroyed should one spring break.

15   The top of the housing containing the door operating means is preferably closed by a removable cover, (not shown) thereby permitting ready access to the parts enclosed therein when necessary or desirable.

20   We do not herein claim as a part of our present invention the washing machine which we have shown and described as this constitutes the subject matter of our copending application, Serial No. 120,710, filed July 6, 1926. The said application relates to the washing machine as an entirety, whereas the present application is restricted to a door operating mechanism adapted for use in a washing machine of the type described.

25   What we claim and desire to secure by Letters Patent is:

30   1. In a closure operating mechanism for dish washing apparatus of the kind comprising a rectangular casing provided with front and back walls and with side walls having similar large openings formed therein respectively and movable doors closing the said openings respectively, the combination with the said doors of a mechanism adapted for simultaneously opening or closing both of them and including a manually operable lever, all parts of the said mechanism other than the said lever being behind the said front wall and the said lever extending in front of the said front wall so as to be readily accessible.

35   2. In a closure operating mechanism for dish washing apparatus of the kind comprising a rectangular casing provided with front and back walls and with side walls having similar large openings formed therein respectively and movable doors closing the said openings respectively, the combination with the said doors of a mechanism adapted for simultaneously opening or closing both of them and including a manually operable lever, all parts of the said mechanism other than the said lever being inside the upper portion of the casing and the said lever extending in front of the said front walls so as to be readily accessible, and a partition in the casing immediately below the said mechanism

40   and forming a chamber therefor separate from the lower portion of the said casing.

45   3. In a closure operating mechanism for dish washing apparatus of the kind comprising a rectangular casing provided with front and back walls and with side walls having similar large openings formed therein respectively and two vertically slidable doors normally closing the said openings respectively, the combination with the said doors of a manually operable horizontally movable lever carried by the casing inside the upper portion thereof and between the planes of the said opposite side walls, and means connecting both of the doors with the said lever so that they will be raised or lowered in unison when the lever is moved.

50   4. In a closure operating mechanism for dish washing apparatus of the kind comprising a rectangular casing provided with front and back walls and with side walls having similar large openings formed therein respectively and two vertically slidable doors normally closing the said openings respectively, the combination with the said doors of a lever located inside the upper portion of the casing and pivoted to the back wall for horizontal movement about a vertical axis, the said lever projecting forward in front of the plane of the front wall and being manually movable transversely between the planes of the side walls, and means connecting both of the doors with the said lever so that they will be raised or lowered in unison when the lever is moved.

55   5. In a closure operating mechanism for dish washing apparatus of the kind comprising a rectangular casing provided with front and back walls and with side walls having similar large openings formed therein respectively and two vertically slidable doors normally closing the said openings respectively, the combination with the said doors of a manually operable horizontally movable lever carried by the casing within the upper portion thereof and between the planes of the said opposite walls, two flexible tension elements each connected at one end to one of the doors and each connected at the other end to the lever, both of the said elements initially extending in the same direction from the lever, and guide pulleys over which the said elements extend between the said lever and the said doors.

60   6. In a closure operating mechanism for dish washing apparatus of the kind comprising a rectangular casing provided with front and back walls and with side walls having similar large openings formed therein respectively and two vertically slidable doors normally closing the said openings respectively, the combination with the said doors of a door operating mechanism including a common spring means carried by the casing adjacent

the top thereof and connected with both doors so as to tend to raise them.

7. In a door operating mechanism, the combination of a casing having at least one vertical side wall with a large opening therein, a movable door normally closing the said opening, a manually operable horizontally movable lever carried by the casing, means connecting the said door with the said lever so that it will be opened or closed when the lever is moved, and a manually releasable means adapted to automatically engage and hold the lever when it reaches a position corresponding to the open position of the door.

15. 8. In a door operating mechanism, the combination of a casing having at least one vertical side wall with a large opening therein, a movable door normally closing the said opening, a manually operable lever carried by the casing and normally movable horizontally, the said lever being also movable vertically to a limited extent, means connecting the said door with the said lever so that it will be opened or closed when the lever is moved horizontally, and a manually releasable means adapted to automatically engage and hold the lever when it reaches a position corresponding to the open position of the door, the said means being manually disengaged by manual movement of the lever vertically.

35. 9. In a door operating mechanism, the combination of a casing having at least one vertical side wall with a large opening therein, a vertically slidable door normally closing the said opening, and a mechanism including a horizontal coil spring connected with the door so as to tend to raise it.

40. 10. In a door operating mechanism, the combination of a casing having two opposite vertical side walls respectively having similar large openings therein, two vertically slidable doors normally closing the said openings respectively, and a mechanism including a horizontal coil spring connected with both doors so as to tend to raise them.

45. 11. In a door operating mechanism, the combination of a casing having at least one vertical side wall with a large opening therein, a vertically slidable door normally closing the said opening, a manually operable horizontally movable lever carried by the casing, means connecting the said door with the said lever so that it will be raised or lowered when the lever is moved, and a horizontal coil spring connected with the lever so as to tend to move it in the door-opening direction.

50. 12. In a door operating mechanism, the combination of a casing having at least one vertical side wall with a large opening therein, a vertically slidable door normally closing the said opening, a manually operable horizontally movable lever carried by the casing, means connecting the said door with the said lever so that it will be raised or lowered

when the lever is moved, a horizontal coil spring located with its ends at opposite sides of the lever and with one end fixedly connected with the casing, and means including a flexible tension element and a pulley for connecting the other end of the spring with the lever so as to tend to move it in the door-opening direction.

70. 13. In a door operating mechanism, the combination of a casing having two opposite vertical side walls respectively having similar large openings therein, two vertically slidable doors normally closing the said openings respectively, a manually operable horizontally movable lever carried by the casing between the planes of the said opposite side walls, and a horizontal coil spring connected with the lever so as to tend to move it in the door-opening direction.

75. 14. In a door operating mechanism, the combination of a casing having two opposite vertical side walls respectively having similar large openings therein, two vertically slidable doors normally closing the said openings respectively, a manually operable horizontally movable lever carried by the casing between the planes of the said opposite side walls, means connecting both of the doors with the said lever so that they will be raised or lowered in unison when the lever is moved, a horizontal coil spring located with its ends at opposite sides of the lever and with one end fixedly connected with the casing, and means including a flexible tension element and a pulley for connecting the other end of the spring with the lever so as to tend to move it in the door-opening direction.

80. This specification signed this 10th day of October, A. D. 1925.

GEORGE WEBB.
FRANK D. JENKS.
